US00D786214S

(12) **United States Design Patent** (10) **Patent No.:** **US D786,214 S**
(45) **Date of Patent:** **** May 9, 2017**

(54) **MOBILE PHONE**

(71) Applicant: **LG Display Co., Ltd.**, Seoul (KR)

(72) Inventors: **Da Bin Kwon**, Seoul (KR); **Jong Seo Yoon**, Seoul (KR); **Ki Hwan Son**, Seoul (KR); **Dong Jin Seo**, Paju-si (KR)

(73) Assignee: **LG DISPLAY CO., LTD.**, Seoul (KR)

(**) Term: **15 Years**

(21) Appl. No.: **29/556,023**

(22) Filed: **Feb. 26, 2016**

(30) **Foreign Application Priority Data**

Aug. 27, 2015 (KR) 30-2015-0043198

(57) **CLAIM**

The ornamental design for a mobile phone, as shown and described.

DESCRIPTION

FIG. 1 is a perspective view of the mobile phone showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image; and,

FIG. 6 is a reference view thereof showing an example of the usage of the subject design.

The broken lines depict environmental subject matter only and form no part of the claim.

1 Claim, 6 Drawing Sheets
